UNITED STATES PATENT OFFICE.

JOSEPH B. STALTER, OF PITTSFORD, NEW YORK.

CRIB.

941,429.

Specification of Letters Patent. Patented Nov. 30, 1909.

Application filed December 23, 1908. Serial No. 468,979.

To all whom it may concern:

Be it known that I, JOSEPH B. STALTER, a citizen of the United States, residing at Pittsford, in the county of Monroe and State 5 of New York, have invented new and useful Improvements in Cribs, of which the following is a specification.

This invention relates to cribs, the object of the invention being to provide a swinging 10 crib which is simple and inexpensive of construction, which may be suspended from suitable supports, in a ready and convenient manner for either outdoor or indoor use, and from which the infant cannot crawl or 15 fall, thus insuring safety without the constant service of an attendant.

The invention consists of the features of construction, combination and arrangement 20 of parts hereinafter fully described and claimed, reference being had to the accompanying drawing, in which:—

Figure 1 is a perspective view of a crib embodying my invention. Fig. 2 is a vertical transverse section of the same.

The crib is of the conventional oblong 25 rectangular form and openwork construction, and may be of either wood or metal, the latter being preferred. It comprises an upper rectangular frame portion 1 and a lower rec- 30 tangular frame portion 2, which may be conveniently made from strips of strap-iron bent into form and each having its ends suitably united.

The end rails of the frame sections 1 and 35 2 are connected by spaced rods or bars 3, while the side rails of said frame sections are connected by spaced rods or bars 4. The bottom of the crib is formed by cross bars or rods 5, closely enough arranged to enable 40 the bedding to be supported thereon without sagging. Preferably the bars 4 and 5 are made of continuous strips of material, each bar 5 being integral with the lower ends of the alining bars 4, providing U-shaped bars 45 or rods which pass through openings in the side rails of the lower frame portion 2 and are terminally fastened to the side rails of the upper frame portion 1. At the center of the crib a U-shaped stop brace 6 is provided 50 in lieu of central rods, its vertical arms 7 being secured at their upper ends to the upper frame portion and integral at their lower ends with the central cross piece 8 of said brace, which passes under and is suitably se- 55 cured to the side rails of the lower frame

portion. Vertical braces 9 of flat strips of material, also take the place of central end rods and are secured at their upper and lower ends to the end rails of the upper and lower frame portions. The upper ends of 60 said strips 9 are extended above the crib body and apertured, as at 10, to receive hooks or the like at the ends of suspension cords, chains or ropes 11, by which the crib may be suspended, like a hammock or in any other 65 manner, from suitable supports, either indoors or outdoors, so as to swing either side- wise or endwise.

It will be apparent from the foregoing description that a crib constructed according 70 to my invention may be manufactured and sold at a low cost, that it may be swung to and fro to lull the child to sleep, and that the parts may be properly proportioned as to render it impossible for an infant to roll 75 or crawl out, whereby safety is insured without the constant service of an attendant.

Having thus fully described the invention, what is claimed as new is:—

A crib comprising an upper rectangular 80 frame portion formed from a single piece of strap metal, a corresponding lower rectangular frame portion also formed from a single piece of strap metal, said frame portions presenting flat side and end rails, the side 85 rails of the lower frame portion being provided with openings, rods connecting the end rails of the frame portions, rods connecting the side rails of the frame portions, cross rods forming the bottom of the crib 90 and integral with the lower ends of the latter named rods, said rods being passed at their points of union through the openings in the side rails of the lower frame portion, U-shaped strap metal braces centrally connecting the side rails of the frame portions and extending transversely beneath the lower frame portion, and strap metal long 95 braces centrally secured to the end rails of the frame portions and having their upper 100 ends projected above the top frame portion and provided with openings to form hangers for connection with suspension devices.

In testimony whereof I affix my signature in presence of two witnesses.

JOSEPH B. STALTER.
